UNITED STATES PATENT OFFICE.

ALBERT H. TAYLOR, OF EASTON, PENNSYLVANIA, ASSIGNOR TO THE
INGERSOLL-SERGEANT DRILL COMPANY, OF NEW YORK, N. Y., A
CORPORATION OF WEST VIRGINIA.

REVERSING MECHANISM FOR ROTARY MOTORS.

No. 820,684.

Specification of Letters Patent.

Patented May 15, 1906.

Application filed August 1, 1905. Serial No. 272,173.

To all whom it may concern:

Be it known that I, ALBERT H. TAYLOR, a citizen of the United States, and a resident of Easton, in the county of Northampton and State of Pennsylvania, have invented a new and useful Improvement in Reversing Mechanism for Rotary Motors, of which the following is a specification.

The object of my invention is to provide certain improvements in reversing mechanism for rotary motors in which the movements of the reversing-valve are manually controlled through the medium of a handle located on the exterior of the motor.

This invention is shown herein as applied to a pneumatic motor of the rotary-piston type adapted for use as a drill.

A practical embodiment of the invention is represented in the accompanying drawings, in which—

Figure 1 represents in top plan a rotary pneumatic motor embodying my invention. Fig. 2 is a side view of the same, portions of the motor being broken away to more clearly show its interior arrangement. Fig. 3 is a horizontal section taken in the plane of the line A A of Fig. 2 looking in the direction of the arrows. Fig. 4 is a top plan view of the reversing-valve and inner top cylinder-head, the valve being at the limit of its rocking movement in one direction. Fig. 5 is a diagrammatic sectional view taken in the plane of the line B B of Fig. 4. Fig. 6 is a top plan view of the valve and inner top cylinder-head, the valve being at the limit of its movement in the opposite direction; and Fig. 7 is a diagrammatic section taken in the plane of the line C C of Fig. 6.

The body of the pneumatic motor of the rotary-piston type in connection with which this invention is shown is denoted by 1, its top and bottom outer cylinder-heads by 2 and 3, and its top inner cylinder-head by 4. The piston-chamber is denoted by 5, and a piston 6, of any well-known or approved form, is mounted eccentrically therein. Ports 7 and 8 lead from the piston-chamber 5 upon opposite sides of the point of contact of the piston with the inner walls of the chamber to vertically-arranged separated passages 9 and 10 in the walls of the body of the motor. The main motive-fluid inlet is denoted by 11, and a vertical passage 12 communicates there-

with, which passage 12 is located in the partition-wall between the passages 9 and 10. 55 The inner top cylinder-head 4 of the motor is provided with a port 13 therethrough, which is at all times in communication with the main fluid-inlet passage 12. Ports 14 and 15 also extend through the inner top head 4 60 upon opposite sides of the port 13, the port 14 being at all times in open communication with the passage 9 and the port 15 being at all times in open communication with the passage 10 in the body of the motor. Ports 65 16 17 extend through the top inner head 4, which ports are at all times in alinement with passages 18 19, which extend vertically through the body of the motor and are in open communication at their lower ends 70 with the interior of the lower outer cylinder-head 3.

A rotary valve 20 is mounted on the inner top cylinder-head 4 in the space 21 between the inner and outer top cylinder-heads, the 75 rotary movement of which valve is limited by a pin-and-slot connection, the slot in the present instance (denoted by 22) being formed in the valve and the pin 23 being secured in position between the inner and outer top 80 cylinder-heads. A handle 24 for rocking the valve is located exterior to the body of the motor and is provided with a shank 25, which extends through a suitably-arranged stuffing-box 26 in the outer top cylinder- 85 head, which shank is secured to the valve 20 between the two heads. This valve 20 is provided with an elongated port 27 therethrough concentric with the ports 13 14 15, the length of the port 27 being such that 90 when the valve is rocked to the limit of its movement in one direction the main inlet passage 12 will be brought into open communication with the passage 9 through the ports 13 and 14 and when rocked to the 95 limit of its movement in the other direction the main inlet-passage 12 will be brought into open communication with the passage 10 through the ports 13 and 15. This elongated port 27 is opened entirely through the valve, so as to keep motive-fluid pressure in the space 21 for holding the valve snugly in its seat on the inner top head 4. This valve 20 is further provided with an elongated bridge-port 28 in its bottom, which port is 100 105 concentric with the ports 14 and 16 and is

arranged to open the port 14 of the passage 9 to the port 16 of the exhaust-passage 18 when the valve is at the limit of its movement in one direction and to close communication to the port 16 when the valve is at the limit of its movement in the opposite direction. This valve 20 is furthermore provided with an elongated bridge-port 29, which is concentric with the ports 15 and 17 and is arranged to open the port 15 of the passage 10 to the port 17 of the exhaust-passage 19 when the valve is at the limit of its movement in one direction and to cut off communication to the port 17 when the valve is at the limit of its movement in the opposite direction.

In operation, supposing the valve to be in the position shown in Fig. 4, the motor will be driven in one direction with its supply of motive fluid passing from the passage 12 through the ports 13 14, passage 9, and port 7, to the piston-chamber 5 on one side of the piston, the other side of the piston being open to the external atmosphere through port 8, passage 10, ports 15, 29, and 17, and exhaust 19. When it is desired to reverse the motion of the motor, the valve may be turned into the position shown in Fig. 6, when the motive fluid will be supplied to the piston-chamber through the passage 12, port 15, passage 10, and port 8, the other side of the piston-chamber at the same time being open to the external atmosphere through the port 7, passage 9, ports 14 28 16, and passage 18.

It will be seen that by mounting the valve between the inner and outer top cylinder-heads I am enabled to provide a very simple and convenient arrangement without the necessity of producing a complicated motor-cylinder, and, furthermore, that the parts are readily accessible and are extremely simple. While I have shown this mechanism in connection with a pneumatic motor of the rotary-piston type adapted for use as a drill, it is to be understood that I do not wish to limit myself to this construction; but

What I claim as my invention is—

1. The combination with the cylinder of a

rotary motor, its top and bottom outer cylinder-heads and its top inner cylinder-head, a piston-chamber, a rotary piston mounted eccentrically therein, said cylinder having therein a fluid-inlet passage, two piston-passages and two exhaust-passages, of a manually-operated reversing-valve mounted on the inner top cylinder-head arranged to direct the motive fluid from the fluid-inlet passage to one of the piston-passages and from the other piston-passage to one of the exhaust-passages.

2. The combination with the cylinder of a rotary motor, its top and bottom outer cylinder-heads and its top inner cylinder-head, a piston-chamber, a rotary piston mounted eccentrically therein, said cylinder having therein a fluid-inlet passage, two piston-passages, and two exhaust-passages communicating with the interior of the bottom outer cylinder-head, of a manually-operated reversing-valve mounted on the top inner cylinder-head arranged to direct the motive fluid from the fluid-inlet passage to one of the piston-passages and from the other piston-passage to one of the exhaust-passages.

3. The combination with the cylinder of a rotary motor, its top and bottom outer cylinder-heads and its top inner cylinder-head, a piston-chamber, a rotary piston mounted eccentrically therein, said cylinder having a fluid-inlet passage, two piston-passages and two exhaust-passages, of a manually-operated reversing-valve having a port for opening the fluid-inlet passage to the one or the other of the piston-passages and also having two bridge-ports for opening the one or the other of the piston-passages to the one or the other of the two exhaust-passages.

In testimony that I claim the foregoing as my invention I have signed my name, in presence of two witnesses, this 28th day of July, 1905.

ALBERT H. TAYLOR.
